PACKER

Cecil H. Sweet, Hobbs, N. Mex.

Application August 11, 1947, Serial No. 768,053

15 Claims. (Cl. 166—12)

1

This invention relates to packers for packing off the space between concentric pipes in a well or the like and has for its general object the provision of such a packer of a type adapted to be expanded radially to form a seal after it has been properly located, and which may be readily removed after it has been set.

Numerous types of packers have been devised which are capable of packing off the annular space between concentric pipes or the like such as are customarily found in well bores. However, even though various expandable type packers have been designed for the purpose of enabling them to be removed with the inner pipe when removal of the inner pipe becomes desirable, it has been found that without exception such packers have in the past been so susceptible of sticking to the outer pipes and of resisting the flexing necessary to enable them to disengage from the outer pipes that as a practical matter they have not proven to be removable. Furthermore, in most instances in which such packers have been designed for the purpose of permitting their removal, their design has been such as made it necessary that the force to be exerted upon the packer for the purpose of dislodging it from its sealed engagement with the outer pipe be transmitted through a pull exerted on the inner pipe. This has prohibited the use of this type of packer in deep wells in which the string of inner pipe is frequently so long that it is scarcely more than able to support its own weight. Obviously in such cases any substantial additional pull on the packer in an effort to release it would cause the inner pipe to break.

It is an object of this invention to provide a packer of the type referred to which may be readily released even though the packing material may have become stuck to the outer pipe.

Another object is to provide a packer of the type referred to in which the force necessary to dislodge the packer when it is desired to remove the same need not be transmitted to the packer by means of added tension on the tubing.

Another object of this invention is to provide a structure of the type referred to in which both the inner pipe or tubing and the packer may receive substantial support from the outer pipe or casing both while the packer is in sealed position and while it is being unseated from its sealed position.

Another object of this invention is to provide a packer of the type referred to in which when it is desired to dislodge the packer from its sealed position, the sealing pressure may first be removed from the packing material.

2

Other objects and advantages of this invention will become apparent from the following description taken in connection with the accompanying drawings wherein is set forth by way of illustration and example one embodiment of the invention.

In the drawings:

Figure 1 is a view partly in elevation and partly in longitudinal cross section illustrating a packer constructed in accordance with this invention in place within an outer pipe or casing, but before the same has been expanded into sealing engagement with the casing.

Figure 2 is a view similar to Figure 1 but showing an extension of the lower portion of Figure 1 and illustrating the supporting means employed in connection with the packer of Figure 1.

Figure 3 is a view similar to Figure 1 but showing the packer of Figure 1 after the same has been distorted into laterally expanded sealing position to seal off the space between the inner and outer pipes.

Figure 4 is a view similar to Figures 1 and 3 but showing the packer after the same has been released from its sealed position.

Figure 5 is a transverse cross section taken along the line 5—5 of Figure 4.

Figure 6 is a fragmentary sectional view on an enlarged scale illustrating the details of structure adjacent the lower end of the body of packing material employed in connection with the packer shown in Figures 1 to 4, inclusive.

Referring more in detail to the drawings, the numeral 1 indicates an outer pipe or casing such as usually employed in connection with oil, gas or other wells.

The packer constructed in accordance with this invention is provided with a tubular mandrel or part 2 having upper end portion 3 provided with internal threads 4 adapted to receive the lower end of the inner pipe or tubing and having its outer surface provided with ridges 5 which may receive a fishing tool or the like in the event it is desired to remove the packer from the well after the well tubing has been unscrewed from the threads 4.

Intermediate its ends the mandrel 2 is provided with an enlargement the lower extremity of which is undercut to provide a downwardly and inwardly facing overhanging shoulder 6.

A body or sealing member 7 of flexible distortable packing material such as natural or synthetic rubber or other substance known to be useful for this purpose, is provided in the form of a complete annulus having normally a wall thickness insufficient to close the space between the

pipe 1 and the mandrel 2. The upper end of this sealing member surrounds a collar 8 and is preferably firmly joined thereto as by means of vulcanization. This collar is externally threaded on its upper end 9 to receive a traveling ring 10 which abuts the upper end of the body 7 of packing material and has an upper end surface of a shape to engage and conform to the downwardly presented surface of the shoulder 6. This traveling ring 10 is of slightly 10 less internal diameter than the collar 8 for a reason presently to be explained.

At its lower end the body 7 of packing material is likewise molded around or vulcanized or otherwise joined to a collar-like member 11 which extends downwardly below the lower end of the body 7. The part which extends below this lower end of the body 7 is, as more clearly illustrated in Figure 6, provided with an intermediate part 12 of reduced external diameter and a lower externally threaded part 13 of slightly larger external diameter than the part 12. The external threads 13 are adapted to threadedly receive the threads 14 of the tubular packer seat 15.

By reference to Figure 1 it will be seen that the packer seat 15 is a part which provides a shoulder facing upwardly toward the body 7 of packing material and opposed to and spaced from the shoulder 6. The packer seat 15 extends downwardly from its upper end and below the lower end of the member 11 is provided with a releasable holding means which in the design shown take the form of one or more shear screws or the like 16. These shear screws are threaded into and through the member 15 and have their inner ends projecting into a channel-like groove formed around the lower end of the mandrel 2 by the external shoulder 17 on this mandrel and the nut 18 threaded to the lower end of the mandrel. When the mandrel and packer seat are so held by the shear screws 16, the opposed shoulders on these respective parts are spaced apart sufficiently to provide room for the body 7 of packing material to be disposed between them in retracted non-sealing condition.

It is to be noted that when the parts are in the positions illustrated in Figures 1 and 3 the upper end of the packer seat 15 overlies a plurality of openings 19 which extend radially through the intermediate portion 12 of the ring 11. The engagement between the packer seat 15 and the body 7 of packing material effectively closes off the openings 19 and prevents flow therethrough.

On the other hand, when the parts are in the position shown in Figures 4 and 6 these openings 19 will open into the space between the packer seat 15 and the packing material 7 and flow will thus be permitted through the openings 19.

The lower end portion of the mandrel is made of slightly smaller internal diameter than the remainder thereof and is provided with a key-way 20 extending therethrough, the bottom of the key-way being substantially the same distance from the axis of the mandrel as the radius of the major portion of the mandrel above the reduced lower end portion.

This key-way 20 is adapted to receive a key or spline 21 formed on the inner mandrel 22. This inner mandrel 22 extends upwardly through the mandrel 2 and terminates at its upper end in a portion of relatively large diameter providing an external downwardly facing shoulder 23.

and a thickened upper end portion 24 having a snug sliding fit within the mandrel 2.

The packer seat 15 at its lower end is internally threaded at 25 to receive a tapered slip expander 26. This tapered slip expander 26 is also internally threaded at its upper end at 27 to receive the lower end of the inner mandrel 22. This inner mandrel 22 is provided with radial openings therethrough just above the threaded connection 27 as illustrated at 28, which are closed by the major mandrel covering same when the packer is fully set and uncovered and opened with the lifting of the major mandrel when moved upward by the withdrawing action on the inner pipe string.

The slip expander 26 is internally threaded at its lower end at 29 to receive the anchor guide 30 which extends downwardly therefrom. This anchor guide 30 is threaded externally at its lower end 31 to receive a lower section of tubing if desired.

Just above its lower end the anchor guide 30 is provided with an enlarged portion presenting an upwardly facing shoulder 32 adapted to limit the downward movement of the control sleeve 33 which sleeve slidably surrounds the guide 30. At spaced intervals around this sleeve 33 there are bowed springs 34 in frictional engagement with the interior of the casing 1. These springs 34 are joined by any suitable means at 35 to the sleeve 33 adjacent the lower ends of springs and adjacent their upper ends are joined at 36 to a floating collar 37. This collar 37 is slidably mounted on a reduced outer diameter upper end portion 38 of the sleeve 33.

Rotatably carried in a groove in the exterior of the sleeve 33 adjacent its upper end is an annular member 39 providing pivotal connections 40 for links 41 which are in turn pivotally secured at 42 to the slips 43. These slips 43 have external downwardly directed teeth 44 adapted to prevent them from being moved downwardly with respect to a surface with which they are engaged. The slips 43 are carried in suitable tapered and dove-tailed grooves 45 so that they cannot move radially outwardly with respect to the slip expander 26 except as they are moved upwardly with respect to this slip expander.

Located within the slip expander 26 is a short tubular member which may be termed a pump out nipple 46 adapted to seat against the upper end of the anchor guide 30. The upper end of this nipple 46 is likewise provided with a tapered seat as shown at 47. This nipple 46 is of slightly less internal diameter than the inner mandrel 22 and the seat 47 is adapted to receive a pump out plug or closure. This plug is formed of a body 48 having upwardly directed sealing cups 49 thereabout of a size to seal within the nipple 46. On its upper end this plug is provided with a flared portion 50 forming a valve adapted to seat against the upper seating end of the nipple 46. For the purpose of removing this plug from the tubing if and when necessary it is provided with an upwardly extending centrally located stem 51 having threads 52 formed on its upper end.

In operation when it is desired to set in a well the packer constructed in accordance with this invention, the same is lowered on a string of tubing or similar inner pipe threadedly secured to the mandrel 2 at 4. While being so lowered the parts are held in the positions illustrated in Figures 1 and 2 by means of the shear screws 16. During this lowering operation the slips 43 are

also held in their inactive position as shown in Figure 2 by means of the engagement between the J-slot 53 on the sleeve 33 and the lug 54 on the anchor guide 30.

When the packer has reached a position at which it is desired to set the same and expand it to form a seal between the inner and outer pipes, the tubing on which the packer is being lowered will be rotated to the left to disengage the lug 54 from the upper end portion of the slot 53, and then lowered to permit this lug 54 to move into the lower end portion of the slot 53. The tubing will then be lowered while the springs 34 will hold the sleeve 33 in substantially the same level. This movement of the tubing will cause movement of the slip expander 26 down between the slips 43 and the consequent radially outward movement of the slips 43. This of course will result in anchoring of the entire device within the outer casing against further downward movement with respect to the outer casing.

In order to set the packer and cause the packing member 7 to expand into sealing engagement with the outer casing, additional weight is slacked off on the tubing thereby forcing the mandrel 2 downwardly with respect to the packer seat 15 and also with respect to the inner mandrel 22. This moves the two ends of the packing material body 7 toward each other and causes this body material to expand laterally until it is in sealed engagement with both the casing 1 and the mandrel 2 as shown in Figure 3. The initial downward movement of the mandrel 2 with respect to the packer seat 15 causes the shearing of the shear screws 16 which theretofore supported the packer seat from the mandrel.

It will be noted that both during the lowering operation and during and after the packing expanding operation described, the openings 19 will be effectively closed by the engagement between the packing material 7 and the packer seat 15 so that fluid may be forced through the inner pipe without any danger that it will leak out into the outer pipe.

When it is desired to remove the packer from the outer pipe, the first step is to take up enough of the weight from the tubing so that the tubing throughout its length is in tension and no part of its weight is resting on the mandrel 2. Sufficient weight should be taken off the tubing so that there will be a tendency for the lower end of the tubing to move upwardly if and when released by the packer.

At this stage opening 28 in the minor mandrel 22 will be uncovered, and the plug illustrated in the lower portion of Figure 3 will be dropped into the tubing and caused to come to rest in sealing engagement with the seat 47. This will prevent further downflow through the tubing whereupon fluid under pressure will be injected into the upper end of the tubing which pressure will be exerted inside the tubing in the upward direction on major mandrel 2 sufficient, when added to the lifting action on the tubing string at the surface, to move the mandrel 2 through packer element 7 and along inner mandrel 22 thus breaking the major mandrel loose from any tendency to adhere to the interior of the packing element while at the same time compression is relieved therefrom by a lifting of the upper packer seat. Continued upward movement of mandrel 2 will uncover openings 28 whereupon the fluid inside the tubing will pass from the interior of the inner mandrel out through the 75

openings 28 to act upon the lower end of the mandrel 2 tending to force it upwardly. In as much as the upper end of the mandrel 2 is rigidly joined to the lower end of the tubing and the upper end of the tubing is free to move upwardly, the fluid under pressure within the tubing will exert an upwardly directed force on the mandrel which will be equal to the product of the unit pressure existing within the tubing multiplied by the area of a circle whose diameter is the same as the outer diameter of the mandrel 2.

It has been found that the force which may thus be exerted tending to move the mandrel 2 upwardly will be very large and in every instance sufficient, either alone or taken with such upward force as may be exerted by a pull on the tubing, to move the mandrel 2 upwardly through the body of packing material 7. As the lower end of the mandrel passes up through the body of packing material it will serve to release the inner surface of the packing material for radially inward movement away from the outer casing thereby removing the sealing pressure between the packing material and the outer casing.

It is to be noted that the traveling ring 10 is slidingly carried on the mandrel 2 so that as the mandrel moves upwardly this ring will not necessarily move upwardly but may remain stationary until the mandrel 2 has been entirely withdrawn from within the packing material 7 whereupon the shoulder provided by the upper end of the nut 18 will engage within the traveling ring 10 and pull it upwardly. By this time, however, all of the sealing pressure between the packing material and the casing will have been removed by the withdrawal of the inner mandrel and the natural tendency of the packing material will be to resume its original shape and to retract from the outer casing. Whatever resistance to this action is provided by deterioration of the packing material or other influences causing the packing material to stick to the outer casing may readily be overcome after the sealing pressure has been removed by the upward pull exerted through the nut 18 on the traveling ring 10 which is attached to the upper end of the sealing material.

As soon as the sealing material has been pulled loose from the outer casing in the manner just described, the ring 11 will be moved upwardly within the packer seat 15 until the threaded section 13 comes into engagement with the threaded section 14 on the packer seat. This will serve to open the passages 19 which extend radially through the ring 11 and permit the fluid pressure within the tubing to be released through these openings 19. This release of fluid pressure may be noted by suitable gauges within view of the operator and will inform the operator that the packer has been released and is ready to be withdrawn from the well. Further upward movement of the mandrel 2 will cause inter engagement between the upwardly facing shoulder within the lower end portion of the mandrel 2 and the shoulder 23 on the exterior of the inner mandrel 22. This engagement will limit the upward movement of the mandrel 2 away from the shoulder on the packer seat 15 and make it possible for the tubing acting through the mandrel 2 to withdraw also the inner mandrel 22 and all of the parts connected therewith through the slip expander 26. It is to be noted that upward movement of the slip expander 26 will cause upward

movement of the anchor guide 32 through the sleeve 33 and that the sleeve 33 meantime will be held by the springs 34 and will prevent the slips 43 from moving upwardly with the slip expander 26. Thus disengagement of the slips 43 from the casing will be produced. If desired, after the slips 43 have become disengaged from the casing, the tubing may be rotated to the right to reengage the lug 54 with the upper horizontal portion of the J-slot 53 thereby locking the slips in disengaged position.

After the tubing and packer have been removed from the well, if it be desired to replace them in the well all that is necessary in the event the packing material 7 has not become deteriorated is to move the parts back to the position illustrated in Figure 1 and put in new shear screws 16. In the event that it should appear that the packing material 7 has deteriorated while in the well and that it needs to be renewed, all that is necessary is to unscrew the packer seat 15 from the slip expander 26 and from the ring 11, unscrew the inner mandrel 22 from the slip expander 26, remove the packer seat and body of packing material, replace the body of packing material and packer seat and put the parts together again.

From the foregoing it will be seen that a simple tool has been provided which is fully capable of carrying out and accomplishing all of the objects and advantages sought by this invention.

Having described my invention, I claim:

1. In a removable packer for use on a pipe string, upper and lower tubular parts providing opposed external shoulders and a tubular mandrel on said pipe string extending through said tubular parts in telescoping engagement with the upper of said parts, a distortable body of packing material about said mandrel between said shoulders, a releasable holding means for initially holding said shoulders and mandrel in fixed spaced relation to each other such as to permit said body of packing material to be disposed between said shoulders in retracted nonsealing condition, said mandrel being of external diameter less than the normal inside diameter of the packing material, and a substantially rigid annular body joined to the upper end of said body of packing material and closely slidably embracing said mandrel, said mandrel having an enlargement on its lower end of a size just large enough to prevent its withdrawal through said rigid annular body whereby upon withdrawal from said body of packing material by raising of the pipe string, said enlargement on said mandrel will engage said rigid annular body and further upward movement of said mandrel will exert a pull through said rigid annular body on the upper end of said body of packing material in a direction to extend said body of packing material longitudinally and contract it laterally.

2. In a removable packer for use on a pipe string, upper and lower tubular parts providing opposed external shoulders and a tubular mandrel on said pipe string extending through said tubular parts in telescoping engagement with the upper of said parts, a distortable body of packing material about said mandrel between said shoulders, releasable holding means for initially holding said shoulders and mandrel in fixed spaced relation to each other such as to permit said body of packing material to be disposed between said shoulders in retracted non-sealing condition, said mandrel being of external diameter less than the normal inside diameter of the packing material

5 and an abutment on said mandrel limiting upward movement of said mandrel away from the shoulder at the lower end of said body of packing material after said mandrel has been withdrawn from said body of packing material by raising of the pipe string.

3. In a removable packer for use on a pipe string, upper and lower tubular parts providing opposed external shoulders and a tubular mandrel on said pipe string extending through said tubular parts in telescoping engagement with the upper of said parts, a distortable body of packing material about said mandrel between said shoulders, releasable holding means for initially holding said shoulders and mandrel in fixed spaced relation to each other such as to permit said body of packing material to be disposed therebetween in retracted nonsealing condition, said mandrel being of such external diameter less than the normal inside diameter of the packing material, a substantially rigid annular body joined to the upper end of said body of packing material and closely slidably embracing said mandrel, said mandrel having an enlargement on its lower end of a size just large enough to prevent its withdrawal through said rigid annular body, whereby upon withdrawal from said body of packing material by raising of the pipe string, said enlargement on said mandrel will engage said rigid annular body and further upward movement of said mandrel will exert a pull on the upper end of said body of packing material in a direction to extend it longitudinally and contract it laterally, and an abutment on said mandrel limiting upward movement of said mandrel away from the shoulder at the lower end of said body of packing material after said mandrel has been withdrawn from said body of packing material.

40 4. In a removable packer for use on a pipe string, upper and lower tubular parts providing opposed external shoulders and a tubular mandrel on said pipe string extending through said tubular parts in telescoping engagement with the upper of said parts, a distortable body of packing material about said mandrel between said shoulders, releasable holding means for initially holding said shoulders and mandrel in fixed spaced relation to each other such as to permit said body of packing material to be disposed between said shoulders in retracted non-sealing condition, said mandrel being of external diameter less than the normal inside diameter of the packing material, and means limiting upward movement of said mandrel away from the shoulder at the lower end of said body after it has been withdrawn from said body by raising of the pipe string, said last mentioned means comprising a tubular part of smaller external diameter than 45 said mandrel slidably interconnecting said mandrel and the part carrying said last mentioned shoulder.

5. In a removable packer for use on a pipe string, upper and lower tubular parts providing opposed external shoulders and a tubular mandrel on said pipe string extending through said tubular parts in telescoping engagement with the upper of said parts, a distortable body of packing material about said mandrel between said shoulders, and releasable holding means for initially holding said shoulders and mandrel in fixed spaced relation to each other such as to permit said body of packing material to be disposed between said shoulders in retracted non-sealing condition, said mandrel being of external

diameter less than the normal inside diameter of the packing material, a substantially rigid annular body joined to the upper end of said body of packing material and closely slidably embracing said mandrel, said mandrel having an enlargement on its lower end of a size just large enough to prevent its withdrawal through said rigid annular body by raising of the pipe string, whereby upon withdrawal of said mandrel from said body of packing material said enlargement on said mandrel will engage said rigid annular body and further upward movement of said mandrel will exert a pull on the upper end of said body of packing material in a direction to extend it longitudinally and contract it laterally, and means limiting upward movement of said mandrel away from the shoulder at the lower end of said body of packing material after said mandrel has been withdrawn from said body of packing material by raising of the pipe string, said last mentioned means comprising a tubular part of smaller external diameter than said mandrel slidably interconnecting said mandrel and the part carrying said last mentioned shoulder.

6. In a removable packer for use on a pipe string, upper and lower tubular parts providing opposed external shoulders and a tubular mandrel on said pipe string extending through said tubular parts in telescoping engagement with the upper of said parts, a distortable body of packing material about said mandrel between said shoulders, releasable holding means for initially holding said shoulders and mandrel in fixed spaced relation to each other such as to permit said body of packing material to be disposed between said shoulders in retracted non-sealing condition, said mandrel being of such external diameter as to permit its withdrawal from said body of packing material by raising of the pipe string after said body of packing material has been distorted into laterally expanded sealing position, and means limiting upward movement of said mandrel away from the shoulder at the lower end of said body after it has been withdrawn from said body by raising the pipe string, said means comprising a tubular part of smaller external diameter than said mandrel and having a tongue fitting in a longitudinal groove in the mandrel slidably and non-rotatably interconnecting said mandrel and the part carrying said last mentioned shoulder.

7. In a removable packer for use on a pipe string, upper and lower tubular parts providing opposed external shoulders and a tubular mandrel on said pipe string extending through said tubular parts in telescoping engagement with the upper of said parts, a distortable body of packing material about said mandrel between said shoulders, releasable holding means for initially holding said shoulders and mandrel in fixed spaced relation to each other such as to permit said body of packing material to be disposed between said shoulders in retracted non-sealing condition, said mandrel being of such external diameter as to permit its withdrawal from said body of packing material by raising of the pipe string after said body of packing material has been distorted into laterally expanded sealing position, a substantially rigid annular body joined to the upper end of said body of packing material and closely slidably embracing said mandrel, said mandrel having an enlargement on its lower end of a size just large enough to prevent its upward withdrawal through said rigid annular body, whereby upon withdrawal of said

mandrel from said body of packing material said enlargement on said mandrel will engage said rigid annular body and further upward movement of said mandrel will exert a pull on the upper end of said body of packing material to extend it longitudinally and contract it laterally, and means limiting upward movement of said mandrel away from the shoulder at the lower end of said body of packing material after said mandrel has been withdrawn from said body of packing material by raising of the pipe string, said last mentioned means comprising a tubular part of smaller external diameter than said mandrel and having a tongue fitting in a longitudinal groove in the mandrel slidably and non-rotatably interconnecting said mandrel and the part carrying said last mentioned shoulder.

8. A removable packer for use on a pipe string having a bore, comprising upper and lower telescoping members having passages therethrough communicating with said pipe bore, the upper member being attached to the pipe string and having a mandrel extending downwardly and having an annular shoulder above the mandrel, and the lower member having concentric upwardly extending tubular portions adapted to receive said mandrel therebetween, the inner of the tubular portions having near its lower end ducts communicating with its passage and the outer of the tubular portions having an annular shoulder facing said first mentioned shoulder; a distortable body of packing material about said members between said shoulders, and releasable holding means for initially holding said shoulders and said mandrel in fixed spaced relation to each other such as to permit said body of packing material to be disposed therebetween in retracted non-sealing condition, said mandrel being of such external diameter as to permit its withdrawal by raising the pipe string from said body of packing material after said body of packing material has been distorted into laterally expanded sealing position, the lower end of said mandrel being exposed to the ducts through said lower member whereby fluid pressure within said bore will urge said mandrel in a direction to withdraw it from said body.

9. In a removable packer for use on a pipe string having a bore, upper and lower tubular parts providing opposed external shoulders and a tubular mandrel on said pipe string extending through said tubular parts in telescoping engagement with the upper of said parts, a distortable body of packing material about said mandrel between said shoulders, releasable holding means for initially holding said shoulders and said mandrel in fixed spaced relation to each other such as to permit said body of packing material to be disposed therebetween in retracted non-sealing condition, said mandrel being of such external diameter as to permit its withdrawal from said body of packing material by raising of said pipe string after the same has been distorted into laterally expanded sealing position, a substantially rigid annular body joined to the upper end of said body of packing material and closely slidably embracing said mandrel, said mandrel having an enlargement on its lower end of a size just large enough to prevent its withdrawal through said rigid annular body, whereby upon withdrawal from said body of packing material said enlargement on said mandrel will engage said rigid annular body and further upward movement of said mandrel will exert a pull on the adjacent end of said body of packing material in a direc-

tion to extend it longitudinally and contract it laterally, and a valve in the lower shoulder communicating with said bore the interior of said parts being sealed from the exterior thereof by the seating of said body of packing material on the shoulder and the valve being opened by upward stretching of the body as the mandrel is withdrawn, whereby when said body of packing material is completely retracted in a lateral direction further upward pull will unseat it from said last mentioned shoulder and release fluid under pressure from within said bore by opening said valve.

10. A removable packer for use on a pipe string having a bore, comprising upper and lower telescoping members having passages therethrough communicating with said pipe bore, the upper member being attached to the pipe string and having a mandrel extending downwardly and having an annular shoulder above the mandrel, 15 and the lower member having concentric upwardly extending tubular portions adapted to receive said mandrel therebetween, the inner of the tubular portions having near its lower end ducts communicating with its passage and the outer of the tubular portions having an annular shoulder facing said first mentioned shoulder; a distortable body of packing material about said members between said shoulders, releasable holding means for initially holding said shoulders and said mandrel in fixed spaced relation to each other such as to permit said body of packing material to be disposed therebetween in retracted non-sealing condition, said mandrel being of such external diameter as to permit its withdrawal from said body of packing material by raising of the pipe string after said body of packing material has been distorted into laterally expanded sealing position, the lower end of said mandrel being exposed to the ducts through said lower member, whereby fluid pressure within said bore will urge said mandrel in a direction to withdraw it from said body, and plug means for closing the passage through said lower member against flow of fluid under pressure therefrom, whereby pressure fluid injected into the upper of said members will increase the fluid pressure within said ducts.

11. An oil well packer assembly, comprising a well casing, telescoping major and minor mandrel sections within the casing having interfering shoulders limiting elongating movement therebetween, the major mandrel being operatively connected with a supporting pipe string, the minor mandrel being operatively connected with a downward movement limiting means and having an internally disposed valve seat, a rubber packing element disposed about the mandrels and embraced at its ends between opposed compressing means carried by the mandrels, openings in the wall of the minor mandrel assembly through which liquid from inside the pipe string may selectively be admitted into the well cavity below the packing element upon closure of the valve seat in the minor mandrel, a drop valve for closing said seat, frangible means holding the mandrel sections in one position as the assembly is lowered into the well but permitting them to take other positions upon being overcome by manipulations of the pipe string after the minor mandrel has reached its downward limit of travel, and means whereby upon a lifting of the pipe string one of the openings in the minor mandrel is uncovered, the major mandrel withdrawn from inside the packer, a pulling action applied to the upper end of the packing element and finally the

minor mandrel, and said packer assembly withdrawn from the well.

12. A removable well packer for use on a pipe string having a bore, comprising upper and lower telescoping members having fluid passages therethrough communicating with said bore, each member having an annular shoulder and said upper member having a mandrel portion extending below its shoulder; a resilient packing body about said packer between said shoulders, said body being fixed to said lower shoulder and said mandrel underlying said body when said members are telescoped together and said shoulders are longitudinally compressing said body; abutments on said mandrel and on the upper end of said body to prevent full withdrawal of said mandrel therefrom; means to close the fluid passage in said lower member; and means for introducing fluid under pressure into the passage of the upper member from the bore, said pressure causing said members to move relatively away from each other and elongate said body.

13. A removable well packer for use on a pipe string having a bore, comprising upper and lower telescoping members having fluid passages therethrough communicating with said bore, each member having an annular shoulder and said upper member having a mandrel portion extending below its shoulder; means to limit elongating movement between said members; a resilient packing body about said packer between said shoulders, said body being fixed to said lower shoulder and said mandrel underlying said body when said members are telescoped together and said shoulders are longitudinally compressing said body; abutments on said mandrel and on the upper end of said body to prevent full withdrawal of said mandrel therefrom; anchor means to secure said lower member at a selected point in said well; means to close the fluid passage in said lower member; and means for introducing fluid under pressure into the passage of the upper member from the bore, said pressure causing said members to move relatively away from each other and elongate said body.

14. A removable well packer for use on a pipe string having a bore, comprising upper and lower telescoping members having fluid passages therethrough communicating with said bore, the upper member being connected to said pipe string and having an annular shoulder and having a mandrel portion extending below its shoulder, and the lower member having concentric upwardly extending tubular portions adapted to receive said mandrel therebetween, the inner tubular portion having near its lower end ducts communicating with its passage and the outer tubular portion having an annular shoulder facing said first mentioned shoulder; a resilient packing body about said packer between said shoulders, said body being fixed to said lower shoulder and said mandrel underlying said body when said members are telescoped together, the lower end of the mandrel blocking said ducts, and said shoulders longitudinally compressing said body; abutments on said mandrel and on the upper end of said body to prevent full withdrawal of said mandrel therefrom; anchor means to secure said lower member at a selected point in said well; means to close the fluid passage in said lower member; and means for introducing fluid under pressure into the passages from the bore, whereby when the pipe string is lifted and said mandrel is pulled upwardly to uncover said ducts the fluid will enter between said tubular portions and

press the mandrel upwardly to cause said members to move relatively away from each other and elongate said body.

15. A removable well packer for use on a pipe string having a bore, comprising upper and lower telescoping members having fluid passages therethrough communicating with said bore, the upper member being connected to said pipe string and having an annular shoulder and having a mandrel portion extending below its shoulder, and the lower member having concentric upwardly extending tubular portions adapted to receive said mandrel therebetween, the inner tubular portion having near its lower end ducts communicating with its passage and the outer tubular portion having an annular shoulder facing said first mentioned shoulder; a resilient packing body about said packer between said shoulders, said body being fixed to said lower shoulder and said mandrel underlying said body when said members are telescoped together, the lower end of the mandrel blocking said ducts, and said shoulders longitudinally compressing said body; abutments on said mandrel and on the upper end of said body to prevent full withdrawal of said mandrel therefrom; means to close the fluid passage in said lower member; and means for introducing fluid under pressure into the passages

from the bore, whereby when the pipe string is lifted and said mandrel is pulled upwardly to uncover said ducts the fluid will enter between said tubular portions and press the mandrel upwardly to cause said members to move relatively away from each other and elongate said body.
